UNITED STATES PATENT OFFICE

ROBERT MARTIN CHAMBERS, OF FINAGHY, BELFAST, IRELAND, ASSIGNOR TO GEORGE MARTIN AND TERESA MARTIN, BOTH OF BELFAST, IRELAND

DEPOSITING MACHINE FOR DOUGH, SEMIFLUID, PASTY, OR LIKE MATERIALS

Original application filed February 7, 1931, Serial No. 514,244, and in Great Britain March 26, 1930.
Divided and this application filed July 15, 1931. Serial No. 551,186.

This invention relates to machines for depositing semi-fluid or pasty material or materials such as dough and other baking mixtures from a bulk supply thereof this case being a division of my prior case, Serial No. 514,244 filed February 7, 1931. The machine, as in my prior case, is of the class which comprises a trough or hopper from which the material to be deposited is discharged by means of reciprocating plungers through one or more cylinders or openings controlled by valves.

According to the present invention, a machine for depositing quantities of plastic or like material from a bulk supply thereof is provided in which the actuating means for the plungers or ejectors comprises a multiple part cam device and means for adjusting the parts of the said cam so that the interval between dwell periods provided by the cam in the motion of the plungers can be varied.

Preferably, the multiple part cam comprises two portions having part of the contour thereof concentric relatively to the cam axis, and part eccentric, the two cam portions being adjustable angularly. Means may be provided whereby large or rough adjustments of the cam parts can be effected quickly, whilst small or final adjustments of the cam portions can be effected by means allowing greater accuracy in the relative positioning thereof.

The invention will now be described, by way of example, with reference to a hand driven machine shown in the annexed drawings, in which,

Fig. 1 is a side elevation, partly in section, of a hand operated depositing machine, in accordance with the invention;

Fig. 2 is an end elevation of the machine looking in the direction of the arrow A, Fig. 1;

Fig. 3 is a plan view of the machine;

Fig. 4 is a detail view of the two-part cam which controls the movements of the plungers;

Fig. 5 is a cross-sectional view of the cam 13, 14, taken on the line 5—5, Fig. 4;

Figs. 6 and 7 are respectively sectional

elevation and plan views of the means for adjusting the movable part 13 of the cam 13—14, described with reference to Figs. 1 to 4.

Referring to the drawings:—

The machine shown comprises a hopper 1 for containing the material to be deposited, and fitted on bottom of same are cylinders 3, the tops of which open into the bottom of the hopper 1. The casting 2 provides supports for flanged wheels 4 on which the whole machine is supported, the wheels 4 running on the edge of the hot plate 5 or other surface on which the material from the machine is to be deposited. The pistons 6 are connected to a top moving beam 7 in each end of which is a guide bar 8 working in guides 9 in brackets 10 attached to the casting which contains the cylinders. The guide bars 8 have racks 8^a cut on them and these racks are engaged by pinions 11, keyed or otherwise attached to a cross shaft 12 and imparting an equal motion to each end of the beam 7. The racks 8^a are operated by a two part cam formed by the parts 13 and 14 and centered at 14^a, the interengagement of the parts 13, 14 so as to be angularly adjustable in relation to each other being shown in the sectional view, Fig. 5. The cam 13—14 acts on a roller 15 fixed to the rack 8^a at one end of the machine. The part 13 of the two-piece cam is centered at 13^a so that for adjustment purposes the part 13 can be rotated round the centre 13^a in order to reduce or increase the length of the acting cam surface and, correspondingly, the length of the stroke of the racks 8^a. The working surface of the cam portion 14 between the points *x* and *y* moves the racks 8^a, and through them, the pistons 6 downward till they assume the position indicated by the dotted lines at 6^a. The part of the cam between *y* and *z* is struck from the centre 14^a; therefore when this part is passing the roller 15 the racks 8^a and the pistons 6 will be stationary. On the movable portion, i. e. the outside portion, 13 of the cam 13—14, the working face between the points *z* and *x* is an arc of a circle centred at 13^a in the part 14 of the cam, the part between the point *v* and the point *x* being struck from the centre 14^a.

(approximately) so that a dead point in the movement of the racks 8^a is provided at the end of the cam movement.

A hinged pawl 16 engages the pin 17^a on the end of the valve barrel 17 turning same from the closed position shown in full lines at Fig. 1 to the open position shown in dotted lines at 17^b Fig. 1, and bringing the pin 17^c to the position now occupied by the pin 17^a.
 5 The bent arm lever 18 centred at 14^a has its limb 18^d (Fig. 2) terminating in a boss 18^e into which is tightly driven a rod 18^b, the latter being slideable through a hole formed diametrically through the head of a pin 18^a turnable in a hole in the part 13 of the cam 13—14. On the other end of the lever 18 and extended beyond the centre 14^a is a pawl 19. This pawl is arranged to engage the pin 17^c as the cam 13—14 moves around its centre 14^a when the point *v* on the cam surface engages the roller 15, so that the onward movement of the cam 13—14 does not move the racks 8^a, but only the pin 17^d is moved round to the position now occupied at 17^a and thereby again closing the valve. On the upward stroke of the cam, the cam face 14^b engages the roller 15 and restores the racks 8^a to the starting position, the point *g* serving to hold the roller in position at the top of the stroke. On the return stroke, or up stroke of the cam, the pawls 16 and 19 pass the pin owing to their being under the action of springs in known manner. The two parts 30 13 and 14 of the cam 13—14 are held in relative position to each other by means of a pin 20 with a suitable crank on its end. The action of this pin is as follows:—
 35

The two parts 13 and 14 of the cam 13—14 are adjusted relative to each other by means shown in Figs. 6 and 7 and comprising a small crank 22 engaging slots 21 in the portion 14 of the cam. The crank 22 is held in position in the slots by means of a spring, and a knob 23 is provided on the top of the crank spindle, for turning same. Fine adjustment of the cam portions 13 and 14 is obtained by turning the knob 23 and the crank pin is held in any position by means of a series of holes 24^a provided in a plate 24 below the knob 23, said holes engaging a pin 25 in the cam portion 13. Quick adjustment of the cam portion 13 is obtained by pulling the knob 23 outwards, thus lifting the crank 22 clear of the slots against the action of a spring. The cam portions 13 and 14 can then be moved relatively to each other.
 50

A peep hole 26 is provided in the movable portion 13 of the cam 13—14 through which a number, corresponding to each of the slots 21, is visible. Letters or other indications are stamped on the upper face of the knob 23 to correspond with the various holes in the bottom of the plate 24. These numbers are used to give an indication of the setting required for each size of deposit.
 65

The valves 17 are shown as revolving cylinders forming stop cocks below each working cylinder 3 and through which the material is discharged by the piston or plunger 6 operated by the bridge bar 7 as hereinbefore described. 70

The arrangement described is such that the amount of active cam surface between the before mentioned "dead" portions of the cam can be varied and the stroke of the plungers thereby varied to suit the requirements. The "dead" point on the cam stops the pillar bars in their downward movement, while the trip action hereinbefore described operates the valves 17, the movement of the cam then continues, pressing down the roller 15 on the pillar 8 and causing the pillars to descend, taking with them the plungers or pistons 6 and discharging the material out through the valves 17 and on to the hot plates, or elsewhere, as desired. This action continues until the "dead" point is reached at the other end of the composite cam 13—14 where again a "dead" point or "dwell" is provided for, which causes the plungers 6 to remain stationary whilst the trip action described operates to close the valve 17. The operating handle 18^c is then returned to its original position and the sequence of operations repeated for the next deposit action. The distance between the two "dead" points or "dwells" on the two portions of the cam can be regulated by causing the one portion 13 to be moved relatively to the other portion 14, to bring the two "dead" portions or "dwells" 100 nearer to each other, or farther from each other as required. 90

It will be understood that the invention is applicable to machines for depositing or ejecting quantities of any viscous, liquid, granular or other substance, such as cake mixtures, jam or flour, and any other substances capable of flowing from a bulk supply into individual ejector vessels or cylinders, all such substances being hereinafter referred to, for convenience, as "plastic materials." 105

I claim:—

1. A machine for depositing quantities of plastic material from a bulk supply thereof, comprising a trough for said bulk supply, a plurality of containers communicating with said trough, ejectors for depositing material entering said containers from said trough, valve means for controlling the discharge of said quantities from said containers, actuating means for said valve means, cam means operatively connected with said ejectors, operating means whereby for a uniform movement of said cam means an intermittent motion is imparted to said ejectors such that during the operation of said valve means dwell periods are provided in which the ejectors are stationary, and means for adjusting said cam means so as to vary the interval between said dwell periods. 115 120 125 130

2. A machine for depositing quantities of plastic material from a bulk supply thereof, comprising a trough for said bulk supply, a plurality of cylinders communicating with said troughs, plungers for ejecting material entering said cylinders from said trough, valve means for controlling the discharge of said quantities from said cylinders, actuating means for said valve means, a multiple part cam device having a contour partly in concentric and partly eccentric with the axis thereof, an operating element adapted to operate said cam, transmission means between said cam and plungers whereby for a uniform movement of the cam an intermittent motion is imparted to said plungers such that during the operation of said valve means dwell periods are provided in which the plungers are stationary, and means for adjusting the parts of said multiple part cam so as to vary the interval between said dwell periods. 70
3. A machine for depositing quantities of plastic material from a bulk supply thereof, comprising a trough for said bulk supply, a plurality of cylinders communicating with said trough, plungers for ejecting material entering said cylinders from said trough, valve means for controlling the discharge of said quantities from said cylinder, actuating means for said valve means, a main cam element having a contour partly concentric and partly eccentric with the axis thereof, a supplementary cam element having a contour partly concentric and partly eccentric with the axis of said main cam element, transmission means between said cam elements and plungers whereby for a uniform turning movement of said cam elements an intermittent motion is imparted to said plungers such that during the operation of said valve means dwell periods corresponding to the concentric contour portions of said cam elements are provided in which the plungers are stationary, and means for relatively adjusting said main cam element and said supplementary cam element so as to vary the interval between said dwell periods. 80
4. A machine for depositing quantities of plastic material from a bulk supply thereof, comprising a trough for said bulk supply, a plurality of cylinders communicating with said trough, plungers for ejecting material entering said cylinders from said trough, valve means for controlling the discharge of said quantities from said cylinder, actuating means for said valve means, a main cam element having a contour partly concentric and partly eccentric with the axis thereof, a supplementary cam element having a contour partly concentric and partly eccentric with the axis of said main cam element, transmission means between said cam elements and plungers whereby for a uniform turning movement of said cam elements an intermittent motion is imparted to said plungers such that during the operation of said valve means dwell periods corresponding to the concentric contour portions of said cam elements are provided in which the plungers are stationary, means whereby said main cam element and said supplementary cam element are directly slidable over each other so as to effect rough adjustment of the interval between said dwell periods, and crank means for effecting exact adjustment of said main cam element and supplementary cam element. 85
5. A machine for depositing quantities of plastic material from a bulk supply thereof comprising a trough for said bulk supply, a plurality of cylinders communicating with said troughs, plungers for ejecting material entering said cylinders from said trough, valve means for controlling the discharge of said quantities from said cylinders, inter-connecting means whereby said plungers are movable in unison, actuating means for said valve means, a two-part cam device having a contour partly concentric and partly eccentric with the axis thereof, an operating handle adapted to turn said cam device about its axis, transmission means between said cam device and plungers whereby for a uniform turning movement of said cam device an intermittent motion is imparted to said plungers such that during the operation of said valve means dwell periods are provided in which the plungers are stationary, means for angularly adjusting the parts of said two-part cam device so as to vary the interval between said dwell periods, and a wheeled support whereby said machine is movable as a whole. 90
